UNITED STATES PATENT OFFICE.

BENJAMIN FRANKLIN BRADLEY, OF PORT NECHES, TEXAS.

OIL-TANK.

1,189,048.

Specification of Letters Patent. Patented June 27, 1916.

Application filed November 14, 1914. Serial No. 872,217.

To all whom it may concern:

Be it known that I, BENJAMIN F. BRADLEY, a citizen of the United States, residing at Port Neches, in the county of Jefferson 5 and State of Texas, have invented new and useful Improvements in Oil-Tanks, of which the following is a specification.

This invention relates to oil tanks, and particularly to oil tank tops and means for mounting the same, whereby in the event of an explosion of the gases or vapors the tank top will be elevated to permit the gas to escape and will then drop back and close the tank and smother the flames, to prevent a conflagration and the destruction of the oil or other inflammable substance stored in the tank.

The object of the invention is to provide a tank which embodies simple and effective means for performing the above stated functions.

The invention consists of the features of construction, combination and arrangement of parts herein fully described and claimed, 25 reference being had to the accompanying drawing in which:—

Figure 1 is a side elevation of an oil tank constructed in accordance with my invention. Fig. 2 is a vertical section through 30 the upper portion of the tank and the tank top. Fig. 3 is a vertical section through one of the posts or standards for supporting the tank top. Fig. 4 is a view in elevation of one of said posts, with parts broken away.

Referring to the drawing, 1 designates the body of the tank, which may be of any suitable form and construction, and 2 designates the movable top of the tank, which 40 may be of any suitable or preferred form, general design and construction. As indicated in the present instance, the tank and top are provided with flanges or opposed surfaces 3 and 4 between which is placed a packing 5, of asbestos rope or other suitable material, whereby undue evaporation of the contents of the tank is prevented and the entrance of dust and other foreign particles obviated. This packing 5 is lashed or 50 otherwise secured to the flange 3, so as to prevent its displacement in case of an explosion.

In accordance with my invention, I provide means for yieldingly supporting the 55 top 2, permitting it to have a desired elevating or opening motion, and adapting it

to drop back with a cushioned action to seal the tank after the opening action. The means designed for this purpose consists of posts or standards 6, each of which comprises a hollow body, tube or cylinder 7 composed of a suitable anchoring base 8 and one or more tube sections, two being shown in the present instance, the said two sections 9 and 10 being provided with flanged coupling members 11 united by bolts 12, and between which coupling members is interposed a partition or abutment plate 13 through which the bolts also pass. Each post is secured at its lower end by the base 8 to the floor or foundation on which the tank rests and is fastened to the top portion of the tank body at its upper end by means of a suitable clip or attaching bracket 14.

Telescopically mounted in the upper tube or section of each hollow post is a plunger tube 15 closed at its lower end by a suitable screw plug or head 16, said tube being slidably mounted in the section 7 of the post body and provided at its upper end with a head 17 or coupling member 17. The heads or coupling members 17 of all of the plungers of the hollow posts employed, which may extend completely around or arranged 80 in groups or series about the tank, are connected at their upper ends by a union bar or strip 18, whereby all or any number of the plunger members are united for movement in unison to exactly the same degree. Disposed within each hollow post body is a coiled cushioning spring 19 which is interposed between the partition or abutment plate 13 and the head 16 of the plunger, as clearly shown in Fig. 3.

As shown, the post sections are adjustably connected as by threaded engagement, with the coupling members 11 and the tubes 7 are in like manner adjustably connected with the bases 8, allowing the post to be varied in length within certain limits so that their heads 17 may be brought to occupy a common level or not as occasion may require in the construction and operation of the parts. It will be evident that by adjusting the plugs 16 in or out the tension of the springs 19 may be varied to regulate the closing action of the top or cover.

It will be understood that in practice the combined strength of the several springs 19 is sufficient to support the weight of the top 2 when said springs are compressed and the

top is seated upon the packing, the top 2 thus being allowed to close fully while its weight upon the packing is practically *nil*, so that in case of an explosion of the gases or vapors contained within the tank it will at once be elevated to an open position, allowing the vapors and the force of the explosion to escape, thereby avoiding any possibility of disruption of the tank. As soon as the force of the explosion is expended, the top 2 will drop back to its normal position and again close or seal the tank and smother any fire which may be caused as a result of the explosion, thus extinguishing the fire and preventing destruction of the oil or other inflammable substances stored in the tank. The plungers 15 being connected with the top 2 and movable freely in the tubular posts, rise easily with the top 2, the springs 19 expanding and maintaining abutting contact with the heads 16, so that upon the dropping of the top 2 back to normal position a cushioning action will be instituted, thus preventing possibility of injury either to the tank body or tank top. The means employed for connecting the union member or members 18 with the tank top may be of any preferred construction, and said union members may form a part of the tank top if desired. It will, of course, be understood that the post may be arranged

interiorly instead of exteriorly of the tank as may be deemed desirable in practice.

I claim:—

In a device of the character described, the combination of a tank open at the top and having a marginal horizontal flange around the inner surface thereof, a vertically movable conical cover for the top of the tank, said cover having upon its underside a horizontal flange disposed in parallel relation to the flange upon the tank, a packing element between said flanges, horizontal bars secured to the outer surface of the cover at opposite sides thereof and projecting beyond the line of the wall of the tank, tubular posts supported upon the exterior of the tank below the respective bars, plungers secured to the bars and movable within the upper portions of the tubular posts, abutments within said posts, and supporting and cushioning springs disposed in the posts between the abutments and plungers and operating to sustain the cover so as to dispose the horizontal flange thereof to rest easily upon said packing.

In testimony whereof I affix my signature in presence of two witnesses.

BENJAMIN FRANKLIN BRADLEY.
